STABILIZING MEANS FOR SHIPS

Otto A. Throndsen, Brooklyn, N. Y.

Application May 10, 1935, Serial No. 20,815

2 Claims. (Cl. 114—126)

The invention relates to means for reducing the rolling and/or pitching of ships as by means of vanes or wings arranged to be extended temporarily from the hull of a vessel.

5 The invention has for an object the provision of a pair or pairs of cooperating vanes of substantial size for minimizing the rolling of ships as well as the pitching, if desired; and which vanes may be extended when required laterally 10 from the hull out of a transverse chamber provided through said hull and located preferably fore and aft.

A further object of the invention is to conserve space on the vessel and to afford a compact structure as in the provision of a compartment extending transversely through the hull of the ship and designed to house a pair of the vane elements; also, to so mount the same therein that the respective members of a pair may 20 be moved in opposite directions with a minimum of applied force and caused to project beyond the hull, which is opened to the sea thereby at the respective ends of the said chamber.

Still another object of the invention resides 25 in the provision of driving means for reciprocating the vanes and located adjacent the said vane-housing compartment.

The invention has for a further object the provision of hollow vanes to serve as pontoons when 30 projecting outwardly from the hull.

In carrying out the invention, there is provided transversely of and entirely through the hull of a ship a suitable compartment which is designed to open to the sea at its opposite ends, the water 35 retained by the compartment, when the vanes are not in use, serving as ballast, if desired. The compartment is so designed as to house normally a pair of vane or wing elements, either in superposed relationship or located alongside each other 40 therein.

Moreover, the outer ends of the respective vanes 45 may serve to close off the said end openings of the compartment when the vanes are not in service, and the said compartment may then be drained of the retained water. The construction of this compartment, furthermore, is such as not to weaken the ship frame, rather reinforcing the structure as in affording a beam tying together the ribs thereof.

50 When desired for use, provision is made for sliding the vanes in opposite directions in the said compartment and through the respective openings in the hull, the vanes being moved laterally beyond the hull a substantial distance 55 to assume more or less horizontal positions and

below the waterline of the ship. This may be accomplished manually, or, preferably, by means of a reversible electric motor, for example, driving a pinion having engagement with corresponding racks carried by the respective vanes 5 and whereby reciprocation thereof may be effected for extending them into the water or withdrawing them into their housing compartment. Suitable anti-friction means are provided to minimize the power required for reciprocating the 10 vanes so that this may be accomplished either manually as well as through the operation of the reversible electric motor.

The nature of the invention, however, will best be understood when described in connection with 15 the accompanying drawings, in which:

Fig. 1 is a side elevation of the hull of a ship which is equipped with the novel stabilizing mechanism; and Fig. 2 is a stern view thereof, showing roll-minimizing vanes extending from 20 the sides of the hull.

Fig. 3 is a plan view of the hull with the vanes at the fore part extended for use.

Fig. 4 is an enlarged fragmentary plan view, 25 with part of the decking broken away, of a portion of the hull provided with a transverse compartment for accommodating a pair of the vanes which are shown in extended position, together with driving mechanism for reciprocation of said vanes.

Fig. 5 is a longitudinal vertical section through the vane-housing compartment as located in a hull; and Fig. 6 is a fragmentary transverse vertical section therethrough, taken on the line 6—6, 30 Fig. 5 of the drawings, and looking in the direction of the arrows.

Referring to the drawings, 10 designates the hull of a vessel as equipped with vanes, herein-after set forth, said vanes being adapted to project from the hull at opposite sides thereof, preferably both fore and aft of the vessel so as to stabilize the vessel both as to rolling and pitching. To this end, there is provided transversely of and entirely through the vessel a horizontally disposed compartment, or compartments 11 and 12, made water-tight by any of the usual and well-known expedients, but which may be opened 40 to the sea at opposite ends.

Within such compartment, for example the compartment 11, Figs. 4—6, is mounted to slide a 50 pair of vanes or wings which may serve as pontoons, and the same are indicated in their extended position. Thus, a vane 13 extends through the opening 14 at one end of the compartment 11 while a vane 15 extends through its opposite 55

opening 16. These vanes may be variously constructed and are preferably hollow to serve as buoyancy members or pontoons tending to stabilize the ship during heavy weather and when extended from the sides of the vessel, as indicated.

The outer ends of the corresponding vanes are preferably flanged or provided with an end plate 17 and 18, respectively, the same being designed to fit the corresponding openings 14 and 16 so as to seal the compartment against the entrance of water when the vanes are not in use and accommodated in their retracted position within the compartment. Waste water valves 19 and 20 may be provided for draining the compartment at such time.

The arrangement of the vanes within the compartment is in accordance with available space and is such that when in retracted position both vanes will be fully accommodated therein, the one, for example, being superposed over the other. The compartment 11 to this end may be divided substantially into two sections by means of an intermediate wall or by rails 21 for guiding the corresponding vanes between the same and the respective top and bottom walls of the compartment. Suitable vertically disposed rollers 22 and horizontally disposed rollers 23 are carried by the respective vanes to cause the same to ride smoothly and freely in the guideway thus provided, so that a minimum power is required in extending the same beyond the vessel's sides and when retracting the same into the compartment.

To effect these reciprocations, suitable power transmission means are provided, for example, the worm 25 and worm wheel 26, the latter driving a shaft 27 which extends through a stuffing box 28 into the compartment 11 and carries at its inner end a pinion 29. The transmission mechanism may be manually rotated as by means of a hand crank 30; but it is preferred to install a reversible electric motor 31 between said crank and the transmission mechanism aforesaid, thus making both power and manual drive available.

Each of the aforesaid vanes 13 and 15 carries a rack as the rack 32 secured, for example in the present embodiment, to the lower portion of the vane 15 and the rack 33 secured to the upper portion of the vane 13. These racks are adapted to be engaged by the pinion 29, rack 32 above and rack 33 below its shaft 27, so that rotation of this pinion will impart motion in opposite directions to the respective vanes, the reciprocations of the said vanes being in accordance with the direction of rotation of the power member.

By this expedient, the vanes may readily be caused to project for use when required a suitable distance beyond the respective sides of the vessel sufficient to afford a very considerable steadyng force to minimize the rolling effect upon the vessel by the waves. The compact pro-

vision for storage of these vanes when not in use admits of making them of relatively large effective surface.

When no longer required, they are retracted within the compartment provided, their ends serving to seal the said compartment against inflow of water; and the water may be retained within the compartment to serve as ballast, or drained through the valves 19 and 20. No structural weakness is developed by the provision of the transverse compartment aforesaid, through cutting of the ship's ribs; but the same acts rather to tie the ship frame together in providing a substantial beam.

Furthermore, in the provision of a pair of the vanes at the after part of the vessel, it will be found that vibration is materially reduced.

I claim:

1. Apparatus for stabilizing a vessel, which comprises a water-tight compartment extending transversely entirely through the hull of a ship and open at its opposite ends, cooperating adjacently disposed elements of substantially the width of the compartment, slidably mounted therein and occupying when withdrawn into the compartment substantially the entire volume thereof and each of said cooperating elements bearing a rack member with the teeth of said rack members oppositely directed, an intermediate pinion engaging continuously both of said rack members, power means located exteriorly the compartment and driving said pinion in one direction for simultaneously extending substantially horizontally the respective cooperating elements through the corresponding end openings of the compartment and in the opposite direction for simultaneously retracting the same wholly within said compartment.

2. Apparatus for stabilizing a vessel, which comprises a water-tight compartment extending transversely entirely through the hull of a ship and open at its opposite ends, and provided with an intermediate longitudinal guide wall, superposed cooperating adjacently disposed elements slidably mounted therein upon opposite sides of the said intermediate wall and occupying when withdrawn into the compartment substantially the entire volume thereof, power means located exteriorly the compartment, transmission mechanism extending therefrom into the said compartment for simultaneously extending substantially horizontally the respective cooperating elements through the corresponding end openings of the compartment and for simultaneously retracting the same wholly within said compartment, and anti-friction members carried by the respective cooperating elements for engagement with said intermediate wall and with the walls of said compartment to guide an element in its reciprocations in said compartment.

OTTO A. THRONDSEN.
